MECHANISM AND PROCESS FOR EFFECTING REVERSE PLATING

Original application filed March 3, 1927, Serial No. 172,331. Divided and this application filed January 8, 1929. Serial No. 330,997.

This application is a division of our co-pending application Serial No. 172,331, filed March 3, 1927.

This invention relates to mechanism and process for effecting reverse plating by or mainly by the action of casting-off or like mechanism.

In order that the principle of the invention may be readily understood, we have disclosed one embodiment of the mechanism and instrumentalities whereby the invention may be practised.

In the drawings:

Fig. 1 is a plan view of the sinker or web holder ring and showing in horizontal section the cams of the sinker cam ring, the top plate of said ring being removed, the parts being positioned for effecting reverse plating;

Fig. 2 is a similar view but with the parts positioned for normal plating;

Fig. 3 represents in side elevation seven different positions of a special web holder or sinker and its companion web holder in the same groove, and the adjacent needles in the formation of a reversely plated loop;

Fig. 3a is a side elevation of the upper part of a needle and representing the position of the yarns or threads in effecting reverse plating with that form of special web holder or sinker shown in Fig. 3;

Fig. 4 represents in side elevation six different positions of a so-called stripe clearer or special instrumentality with its companion regular web holder or sinker in the same groove, and the adjacent needle, in effecting normal plating, preferably in lengthwise stripes between reverse plating stripes;

Fig. 4a is a view in side elevation of a needle and showing several positions of the yarns or threads in effecting normal plating and Fig. 5 is a detail representing a modification.

In the United States patent to Robert H. Lawson, No. 1,605,895, dated November 2, 1926, Reissue No. 16,584, dated April 5, 1927, there are disclosed means for effecting reverse plating by the action of casting off mechanism, whereby lengthwise extending stripes may be formed in hosiery or other knitted

fabrics. In the United States patent to Robert H. Lawson, No. 1,605,896, dated November 2, 1926, there is disclosed means for effecting reverse plating through the action of casting off mechanism, the transverse movements whereof are selectively governed, whereby a great variety of patterns may be provided.

In the present application means are disclosed constituting improvements on the mechanism shown in both of said patents. The mechanism shown in Figs. 1 and 2 hereof is particularly adapted for use in connection with any form of means selectively governing the transverse movements of the casting off mechanism or of the instrumentalities moving transversely of the needles in effecting reverse plating.

Referring first to that form of mechanism shown in Figs. 1 and 2, it is to be understood that the same is preferably used with means selectively governing the transverse movements of the special instrumentalities, such means being preferably one or more disks of the general types shown at 44 and 45 in the said patent to Lawson, No. 1,506,896. It is deemed unnecessary to illustrate herein such disks and their operating means, but reference is made to that patent for a full disclosure of said disks and their manner of operation in selectively positioning the special instrumentalities for movement transversely of the needles.

Referring more particularly to Figs. 1 and 2, the web holder bed ring is indicated at 1, it having radial or transversely extending grooves 2 for receiving the regular web holders indicated at 3 in Fig. 3, and also for receiving the special instrumentalities indicated at 4 in said figures. The sinker cam ring, the top plate whereof has been removed from Figs. 1 and 2, is provided with a series of cams providing different pathways, in the inner one of which the regular web holders and in the two outer ones of which the special instrumentalities are guided, depending upon whether normal or reverse plating is being effected. The cam construction shown in Figs. 1 and 2 are identical, it being understood that in Fig. 1 are shown or indicated 100

the position and movements of the regular web holders and special instrumentalities in effecting reverse plating, whereas in Fig. 2 are shown or indicated the positions and movements of the parts in effecting normal plating, as well as for clearing the stripe for and during normal plating.

As shown in Figs. 1 and 2, we provide an outer cam 5 of general segmental form and 10 extending from the vertically movable, inclined cam 6, which is similar to and is operated in the same manner as the cam edge 72 of the patent to Lawson No. 1,605,896. The purpose of the said cam 6 is to move all the 15 special instrumentalities into the outer pathway.

Radially within the segmental cam 5 is a somewhat similar cam 7 sufficiently spaced from the cam 5 to provide a pathway wherein 20 may be received the butts of the special instrumentalities in effecting reverse plating. Radially inside the cam 7 is provided a pathway wherein at all times the butts of the regular web holders or sinkers 3 ride, it being 25 understood that the special instrumentalities 4 are of greater length than the regular sinkers or web holders 3, as clearly shown in Figs. 3 and 4. When the cam 6 is elevated, the special instrumentalities may ride into 30 the pathway between the cams 5 and 7. The cam 7 may extend in substantially annular form entirely about the circle of needles excepting for the separate cams shown at 8 and 9 in Figs. 1 and 2. Radially outside of 35 the separate cam 9 is a cam 10 between which and the cam 9 the butts of the special instrumentalities ride. The cam 7 at the end thereof nearest the cam 8 is shaped as indicated at 40 11 to effect radially outward movement of the regular web holders.

The segmental cam 5 is provided with an inwardly sloping or inwardly extending end part 12, the purpose of which is to move the special instrumentalities radially inward at 45 an earlier point circumferentially considered, or, in other words, at an earlier point in the stitch forming operation, than the regular web holders are moved inward at or near the casting off point.

50 The purpose of this action is substantially that described in said Lawson Patent No. 1,605,895, now Reissue No. 16,584. Slightly circumferentially beyond the point where the special instrumentalities are so moved inward, that is, to the left thereof viewing Fig. 1, the inner edge of the cam 9 is sloped inward as indicated at 13, such slope terminating in the point 14, circumferentially beyond which the edge of the cam 9 slopes again 55 outwardly as indicated at 15. The purpose of the slope 13 up to the point 14 is to force the regular web holders inwardly in the regular stitch forming operation.

Assuming that the inclined cam 6 has been 60 elevated, the disks or other selective mecha-

nism, one type whereof is shown in the said Lawson Patent No. 1,605,896, move into the pathway between the segmental cams 5 and 7, the butts 16 of those special instrumentalities 4 which are thus selected, the other special 70 instrumentalities 4 remaining in the pathway radially outside of the cam 5. In the continued movement of the parts, the said selected special instrumentalities 4 are projected inward by the inclined edge 12, hereinbefore referred to, and very shortly thereafter the regular web holders or sinkers 3, whose butts 17 ride in the inner pathway radially inside of the cam 7, are also projected inward.

75 The result is to effect reverse plating by reason of such inward or transverse movement of the special instrumentalities 4.

In Fig. 3 we have represented seven positions of the special instrumentalities 4 and the regular web holders 3 in effecting such 80 reverse plating. In said figure, there is represented a black yarn 18 which in normal plating appears at the inner face of the fabric and a white thread 19 which in normal plating appears at the outer face of the fabric.

The greater tension is desirably imparted to the thread 19. The two threads 18, 19 are fed in a plating relation and bear substantially the same relation to each other at their 90 point of introduction as is indicated in Fig. 30 of said Reissue Patent No. 16,584. In the inward movement of the special instrumentalities 4, the upright edge 20 of each special 95 instrumentality participating in reverse plating, engages both of the threads 18, 19 and presses against and pushes the same during such inward movement. At the same time the adjacent needle 21 is descending in the 100 formation of the loop and as the greater tension is upon the white thread 19, it moves first into the notch 22 of the special instrumentality 4. The said white thread 19 is permitted to enter said notch 22, since the notch 23 of the regular web holder 3 substantially 105 registers with the notch 22. The thread 18 having less tension thereon than the thread 19, or if desired being free or substantially free from tension, does not enter into the notch 22 in advance of the thread 19, but does 110 follow the same thereinto. The result, however, is to effect reverse plating and therefore to cause the black thread 18 to appear 115 at the outside of the fabric.

115 It will be observed that each special instrumentality 4 has a forward prolongation 24 whose upper edge 25 is provided with a hump 26, the inclined edges 27, 28 whereof converge and meet at the point 29. Said hump 26 functions in no way during reverse 120 plating. In Fig. 3 we have represented the several positions of the two threads 18, 19 in forming a loop of reverse plating.

125 In Fig. 4 we have represented six positions of a special instrumentality 4 and a regular 130

web holder or sinker 3 in effecting normal plating. We have not attempted to describe the formation by reverse plating of any particular pattern. It will be understood that all those special instrumentalities 4 which are not in any course participating in effecting reverse plating on the needle pertaining thereto, have their butts riding in the outer pathway, that is, the pathway radially out-
10 side of the segmental cam 5 of Figs. 1 and 2.

Referring to Fig. 4 and assuming that the special instrumentality 4 there shown has its butt 16 in said outer pathway, it will be evident that such special instrumentalities 4 as are in the outer pathway are moved inward in accordance with the formation at the outer edge of the said cam 5. The result of having the said special instrumentalities 4 in the outer pathway is to prevent their upright edges 20 from engaging either thread 18 or 19, and hence such instrumentalities when in said outer pathway cannot participate in effecting reverse plating. Therefore, normal plating results at the needle pertaining there-
20 to, as, for example, at the needle 21 shown in Figs. 4 and 4a.

In effecting such normal plating, however, the hump 26 does function and acts in accordance with such function to clear the stripe or in other words to insure the perfection of and continuance of normal plating following the last wale of reverse plating and until reverse plating again commences upon the needle pertaining to such special web instrumentality 4.

Viewing Fig. 4, it will be observed that although the upright edge 20 does not engage either thread 18 or 19, the hump 26 does engage both threads during the downward movement of the needle 21 and that the black thread 18 is caused to slide down the inclined edge 28 while the white thread 19 is caused to slide down the inclined edge 27. Thus the two threads 18, 19 are separated. Such separation, while sufficient for the purpose, is, however, merely momentary, as in the further inward movement of the special instrumentality 4 (as shown in the fifth position in Fig. 4), both threads are engaged by the sloping edge 28. The result of the action of said hump, however, is to ensure that the black thread 18 goes to the inner face of the fabric, and the white thread 19 which preferably is tensioned, goes to the outer face of the fabric.

55 It is not necessary in the practice of the invention to differentiate the tension upon the two threads, or to place the thread 19 under tension or greater tension than the thread 18, inasmuch as the hump 26 effects the separation of the two threads in normal plating and ensures not only that the stripe or area of normal plating will be perfect and without any reverse plating, but renders any difference in tension in the two yarns necessary.

65 We have not herein represented the cam

means for moving special instrumentalities transversely of the needles in effecting reverse plating, but it is to be understood that said cam means may be those shown in the parent application hereof, it being unnecessary to illustrate the same in this application, which is more particularly directed to the instrumentalities which are operated upon by the cam and other mechanism.

The number of special cams employed may be varied as desired, and if but a single special cam moving in the same horizontal plane be employed, all the butts of the special instrumentalities are of the same length. If, however, two or more such special cams are employed, or if the single special cam itself be selected through being caused to operate in two or more horizontal planes by pattern means, the butts of the special instrumentalities will contrast among themselves according to the number of the said special cams or according to the horizontal planes of operation of such single special cams. For example, if there be two special cams one overlying the other, the lower of said special cams will act upon the lower butts and the overlying special cam will act upon the longer butts. In Fig. 5 I have illustrated two cams 48, 51 respectively, and special instrumentalities having two different lengths of butts 16 and 16a to be engaged by said two cams. In any such construction the butts of the special instrumentalities contrast among themselves according to the number of cams employed.

Having thus described one illustrative embodiment of the invention and the best mode known to us for carrying out the process thereof, we desire it to be understood that although specific terms are employed, they are used in a generic and descriptive sense and not for purposes of limitation, the scope of the invention being set forth in the following claims.

1. An instrumentality adapted for use in normal and reverse plating and adapted to be moved in a groove extending in a direction transversely of the needles, said instrumentality having a substantially upright edge adapted to engage and push two threads fed in a plating relation, said instrumentalities having in advance of said upright edge a forward projection provided with a hump-like formation functioning only in normal plating momentarily to separate the two threads, thereby clearing the normal plating stripe.

2. An instrumentality adapted for use in normal and reverse plating and adapted to be moved in a groove extending in a direction transversely of the needles, said instrumentality functioning in reverse plating to engage both threads, and in the loop forming operation insuring reverse plating and having a formation sufficiently in advance of the part

- which in reverse plating engages both threads, to insure normal plating.
3. An instrumentality adapted to move transversely of and between the needles and having an edge adapted to engage at least one of the threads in reverse plating and cooperating with the adjacent needles in securing reversal of the threads and also having a sloping formation substantially in advance of the first mentioned edge and adapted to engage both threads in normal plating and so control their positions as to insure normal plating.
4. A web holder or like instrumentality adapted to be moved in a groove transversely of the needles and having a substantially upright edge to engage both threads during reverse plating and having inwardly in advance of said edge a sloping formation adapted to engage both threads in normal plating to prevent accidental reverse plating to insure normal plating.
5. That process of effecting striped plating in knitted fabrics consisting in feeding a back thread and face thread to the needles so as to effect normal plating, moving certain thread engaging instrumentalities transversely to the needle series at an abnormally early point in the loop forming operation so as to effect thread engagement in such manner as to cause relative change in the position of the threads, whereby, when thread formation by the needles is effected, reverse plating is produced at the wales pertaining to said certain thread engaging instrumentalities, and in effecting normal plating moving said thread engaging instrumentalities transversely to the needle series without causing relative change in the position of the two threads, but effecting momentary separation of the two threads to prevent the accidental occurrence of reverse plating when normal plating is desired.
6. A sinker like instrumentality for use in plating adapted for in and out movement between the needles of a knitting machine having an upper nib, and below and in advance thereof a hump-like thread engaging formation acting as a line evener in clearing the normal plating stripe, said upper nib having directly therebelow a horizontal notch or recess which is in the rear of said hump-like formation.
7. A sinker like instrumentality adapted for in and out movement between the needles of a knitting machine having an upper nib, and below and in advance thereof a hump-like formation functioning in normal plating momentarily to separate the two threads, thereby clearing the normal plating stripe.
8. A sinker-like instrumentality adapted for sliding movement in a groove between the needles of a circular knitting machine having below the extreme top thereof and substantially in advance thereof, a hump-
- like formation consisting of an upwardly and rearwardly inclined forward edge and a downwardly and rearwardly inclined succeeding edge, acting as a line evener in clearing the normal plating stripe.
9. An instrumentality adapted to move transversely of and between the needles and having an edge adapted to engage at least one of the threads in reverse plating and cooperating with the adjacent needles in securing reversal of the threads, and having inwardly in advance of said edge an upward projection adapted to engage both threads in normal plating to prevent accidental reverse plating, i. e. to insure normal plating.
10. A sinker-like instrumentality adapted for to and fro movement between the needles of an independent-needle knitting machine, said instrumentality having below the extreme top thereof and substantially in advance thereof, a hump-like formation consisting of an upwardly and rearwardly inclined forward edge and a downwardly and rearwardly inclined succeeding edge, acting as a line evener in clearing the normal plating stripe.
11. A sinker-like instrumentality adapted to move transversely of and between the needles and cooperating therewith in the stitch forming operation, and having a formation which in normal plating engages both threads to prevent accidental reverse plating.
12. A sinker-like instrumentality adapted to move transversely of and between the needles and cooperating therewith in the stitch forming operation and having an upwardly extending projection which in normal plating functions to prevent accidental reverse plating.
13. For use in an independent-needle knitting machine, an instrumentality adapted to move transversely of the needle series in the loop forming operation and having a yarn engaging reverse plating edge and also having a hump, such as 26, to engage and momentarily separate the two threads in normal plating.
14. For use in an independent-needle knitting machine, an instrumentality adapted to move transversely of the needle series in the loop forming operation and having a hump, such as 26, to engage and momentarily separate the two threads and thereby participating in effecting normal plating.
- In testimony whereof, we have signed our names to this specification.
- JOHN LAWSON.
